US00D923189S

(12) **United States Design Patent** (10) **Patent No.:** **US D923,189 S**
(45) **Date of Patent:** **** Jun. 22, 2021**

(54) **FOOT MASSAGER**

(71) Applicant: **Weijie Cai**, Singapore (SG)

(72) Inventor: **Weijie Cai**, Singapore (SG)

(**) Term: **15 Years**

(21) Appl. No.: **29/706,801**

(22) Filed: **Sep. 24, 2019**

(30) **Foreign Application Priority Data**

Mar. 25, 2019 (HK) 1913296.2

(51) **LOC (13) Cl.** **28-03**

(52) **U.S. Cl.**

USPC **D24/213**

(58) **Field of Classification Search**

USPC D24/192, 200, 204, 211, 212, 213, 214,
D24/215

CPC A61H 2205/12; A61H 15/00; A61H
2205/125; A61H 2001/027; A61H 7/007

(74) *Attorney, Agent, or Firm* — Baker & McKenzie LLP

(57) **CLAIM**

The ornamental design for a foot massager, as shown and described.

DESCRIPTION

FIG. 1 is a front perspective view of my new design;

FIG. 2 is a back perspective view thereof;

FIG. 3 is a front elevation view thereof;

FIG. 4 is a back elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a front perspective view of my new design in an extended position;

FIG. 10 is a back perspective view thereof;

FIG. 11 is a front elevation view thereof;

FIG. 12 is a back elevation view thereof;

FIG. 13 is a right elevation view thereof;

FIG. 14 is a left elevation view thereof;

FIG. 15 is a top plan view thereof; and,

FIG. 16 is a bottom plan view thereof.

The broken lines shown in the figures are for the purposes of illustrating portions of the foot massager, which forms no part of the claimed design.

1 Claim, 16 Drawing Sheets
